Attorney.

UNITED STATES PATENT OFFICE.

ELIE BENOIT, OF WORCESTER, MASSACHUSETTS.

SELF-CLEANING CUSPIDOR.

SPECIFICATION forming part of Letters Patent No. 651,475, dated June 12, 1900.

Application filed March 26, 1900. Serial No. 10,235. (No model.)

To all whom it may concern:

Be it known that I, ELIE BENOIT, a citizen of the United States, residing at Worcester, in the county of Worcester and State of Massachusetts, have invented certain new and useful Improvements in Self-Cleaning Cuspidors, of which the following is a specification.

My invention relates to self-cleaning cuspidors, and more particularly to an improved 10 construction of the cuspidor shown in my United States Letters Patent No. 570,217.

The object of my present invention is to simplify and cheapen the construction of the valve mechanism and to provide for the flow 15 of water into the cuspidor, if desired, without discharging the contents thereof, as will be hereinafter described.

Referring to the drawings, Figure 1 is a plan view of a cuspidor embodying my improvements. Fig. 2 is a central vertical section on line 2 2, Fig. 1, looking in the direction of the arrow, same figure.

In the accompanying drawings, 1 is the cuspidor, of basin shape, intended to be set into 25 the floor, so that its top surface will be flush with the floor and secured thereto by screws 2, as shown, or otherwise.

The cuspidor 1 has a removable perforated top 3, which is made with openings therein, 30 preferably as shown, and is held in place in any suitable way, as by a pin 3', extending into a slot or opening in the inwardly-extending flange 1' on the cuspidor 1, as shown in Fig. 2.

35 The cuspidor 1 has an outlet or discharge a through its bottom, an overflow b on one side, and an inlet c on one side, through which inlet the water flows into the cuspidor.

I will now describe my valve mechanism, to 40 which my present improvements more particularly relate. The cylindrical valve shell or casing 4 is fast in the inlet-opening c in the cuspidor 1. Within the casing 4 is a spring-actuated valve 5, having the taper portion 5' 45 to fit in the taper valve-seat in the casing 4 and the stem 5" to extend through the end of the casing 4, as shown. A spiral spring 6, bearing at one end against the valve 5 and at its other end against a pin 6' in the open 50 end of the casing 4, acts to hold the valve 5 closed and prevent the entrance of water through the opening 4' in the casing 4 into the

cuspidor. In connection with the valve 5, which controls the inflow of water into the cuspidor, I use a plug or stopper 7, which fits 55 over and closes the outlet or discharge-opening a in the cuspidor and an intermediate connection consisting of a pivoted lever or arm 8. The plug 7 preferably consists of a disk d, of leather or rubber, secured between two 60 metal plates or disks e and f, as shown. A bolt 9 extends loosely through a central opening in the plug 7 and through a hole in the free end of the lever or arm 8, with its head 9' resting on the upper surface of said lever, 65 as shown. The nut 9" on the bolt 9 may be turned on or off to adjust the length of the bolt between the head 9' and the nut 9", as desired. The lever or arm 8 is pivoted at 8' between two ears or projections g on the under side of the valve-casing 4 and has an integral upwardly-extending projection 8", extending in front of and adapted to engage the projecting end of the valve-stem 5", as shown. A yoke or fork piece 10 straddles the valve-casing 4 and is pivoted at its lower forked end 70 to the end of the lever 8, which projects beyond the pivotal support of said lever, as shown.

An operating removable key or tool 11 80 (shown by broken lines, Fig. 2) is used to open the valve 5 and will allow the flow of water into the cuspidor without raising the plug 7 to discharge the contents and will also open the valve and raise the plug 7 to discharge 85 the contents of the cuspidor. The key 11 extends through an opening h in the top 3 and engages the upper end of the fork-piece 10 to operate the lever or arm 8 and open the valve 5 to allow the inflow of water and also 90 raise the plug 7 for the discharge of the contents. A slight downward movement of the key 11 will communicate a slight tilting motion to the arm 8, as shown by the lower dotted lines in Fig. 2, which, through engagement of the projection 8" on the lever 8 with the valve-stem 5", will partially open the valve 5 to allow the inflow of water through opening 4' without raising the plug 7. A greater downward movement of the key 11 will open 95 the valve 5 farther and also raise the plug 7, as shown by the upper broken lines, Fig. 2, to allow a full flushing of the cuspidor and the discharge of its contents.

The advantages of my improvements will be readily appreciated by those skilled in the art. I provide for an inflow of water without discharging the water or contents already in the cuspidor and also for a simultaneous flushing and discharge.

It will be understood that the details of construction of my improvements may be varied, if desired.

10 Having thus described my invention, what I claim as new, and desire to secure by Letters Patent, is—

15 1. A cuspidor, having a discharge-opening, an inlet-opening, a valve at the inlet-opening, with a projecting valve-stem and a pivoted lever, carrying a plug or stopper for the discharge-opening at one end, and having a projection at its other end to engage the valve-stem, said lever adapted to be engaged by an 20 operating-key to operate the valve and plug, substantially as shown and described.

25 2. A cuspidor, having a discharge-opening, an inlet-opening, a valve at the inlet-opening, with a projecting valve-stem and a pivoted lever having loosely attached to one end thereof a plug or stopper for the discharge-opening, and a projection at the other end of said

lever to engage the valve-stem, and means for operating said lever to partially open the valve without raising said plug, substantially 30 as shown and described.

3. A cuspidor, having a discharge-opening, an inlet-opening, a valve at the inlet-opening, with a projecting valve-stem and a pivoted lever, and a plug or stopper for the discharge-opening attached to said lever, and a projection on said lever to engage the valve-stem, and means for operating said lever to open the valve and raise the plug, substantially as 35 shown and described.

4. A cuspidor, having a discharge-opening, an inlet-opening, a valve at the inlet-opening, with a projecting valve-stem and a pivoted lever, having a plug for the discharge-opening at one end, and a projection at the other 40 end to engage the valve-stem, and a yoke or fork pivoted on said lever, to be engaged by an operating-key, to operate the valve and plug, substantially as shown and described.

ELIE BENOIT.
